BASEBOARD WARM AIR DISTRIBUTOR

William H. Simpson, Woodacre, Calif.

Application October 31, 1952, Serial No. 318,023

1 Claim. (Cl. 98—40)

This invention relates to a baseboard warm air distributor. More particularly, the invention has reference to a distributor of the character stated which can be of sectional construction, and capable of ready installation either in new buildings or in buildings previously erected.

It is proposed, in accordance with the present invention to provide a baseboard warm air distributor which will be so formed as to be readily usable either for perimeter heating, or for placement under windows of varying lengths, the distributor constituting the present invention being formed for this purpose in sections, which can be readily connected in any desired number or sections in any desired arrangement, to accomplish the desired heating installation.

Another important object is to provide a baseboard warm air distributor which will be so formed as to be usable with forced air heating systems of all types.

Still another object is to provide a baseboard warm air distributor which will have incorporated therein a distributing grid slide, which slide will be so formed as to make it possible to restrict the air flow to insure even distribution.

Yet another object is to provide a baseboard warm air distributor assembly which will be so designed as to permit ducts of various sizes to be stubbed either into the back of the distributor, or through the bottom, thus to permit use of the distributor in any of various buildings, including buildings which, by reason of their age, have side walls that are difficult to open.

A further object of importance is to provide a warm air distributor which will make it possible to obtain results such as those produced by a steam pipe convector, the distributor being so designed, in this connection, as to permit fresh air to be introduced into the warm air distributor, if desired.

Heretofore, it has been proposed to provide warm air distributors of the baseboard type, but to my knowledge, none of these has proved commercially feasible, and I believe this may be due to the fact that those distributors of which I have knowledge have been so designed as to make it difficult, if not impossible, to adjust pressure and air flow within the distributor in a manner effective to obtain an equalized distribution throughout the length of the assembly. This characteristic of the instant invention, it may be noted, facilitates the heating of the walls and floor area, while at the same time permitting cold air from the floor to be mixed with hot air rising at the walls of a room.

Other objects will appear from the following description, the claim appended thereto, and from the annexed drawings in which like reference characters designate like parts throughout the several views, and wherein:

Figure 1 is a fragmentary perspective view through a portion of a building in which a warm air distributor formed in accordance with the present invention is installed;

Figure 2 is an enlarged transverse sectional view through the warm air distributor constituting the present invention;

Figure 3 is a fragmentary front elevational view;

Figure 4 is a sectional view taken substantially on line 4—4 of Figure 2; and

Figure 5 is a schematic or diagrammatic representation illustrating the air flow possible when a distributor formed in accordance with the present invention is being used.

Referring to the drawings in detail, at 10 I have designated generally a portion of a building in which is in-

2

stalled the warm air distributor constituting the present invention, said building having an interior wall 12 and a floor 14.

The device constituting the present invention has been designated by the reference numeral 16, and is adapted to receive warm air flowing thereto from a duct 18.

The duct 18 is adapted to comprise part of a conventional forced air heating system, the device constituting the present invention being readily connectible to the outlet end of the duct, either as a new installation, or as a conversion unit to be substituted for outlet means previously associated with the duct 18 in an older home.

The warm air distributor constituting the present invention can be considered, when viewed in cross section, as having an outer casing and an inner liner or casing, said casing and liner being of hollow formation, and being formed to any desired length. Preferably, the outer casing and its associated liner will be formed as a section of a predetermined length, to be assembled with other sections in providing for the desired installation. Although a single straight section has been illustrated in the drawings, it will of course be understood that corner sections can be provided, having right angled bends therein, as well as other sections of different shapes, selected according to the particular installation to be made.

In any event, considering the formation of the outer casing, said outer casing is provided, in the illustrated example of the invention, with a vertically disposed back wall 20 adapted to be mounted against the interior wall 12 of the building 10. At its upper edge, the back wall 20 is formed with a forwardly directed flange 22. At its lower edge, the back wall 20 is integral with the rear edge of the bottom wall 18' of the outer casing, said bottom wall 18' being integrally connected, at its front edge, with the bottom edge of a vertically disposed front wall 24. Front wall 24 merges, at its upper edge, into a rearwardly and upwardly inclined top wall 26, said top wall 26 merging into a horizontal rear edge portion 28 overlying and secured in any suitable manner to the flange 22.

It will be seen from the above that the outer casing can be made from a single sheet of metal material, bent to shape to impart to the outer casing the desired cross sectional appearance.

In the lower edge portion of the front wall 24 of the outer casing, I form a longitudinal series of floor outlet openings 30, said openings being so arranged as to permit air to be discharged outwardly therethrough along the floor 14, in the manner shown in Figure 5. In the top wall 26, I provide, in the illustrated example of the invention, two straight, parallel rows of wall outlet openings 32, said openings 32 being adapted for the discharge of air therethrough upwardly along the wall 12 (see Figure 5).

The inner liner or casing includes an inner front wall 34 extending vertically from the bottom wall 18', and formed at its lower edge with a rearwardly extended longitudinal flange 36, which flange can be secured in any suitable manner to the bottom wall 18'. The inner front wall 34 of the inner liner is spaced rearwardly from and is in closely spaced relation to the front wall 24 of the outer casing, thereby to define a front chamber 35 extending the full length of the assembly. The front chamber 35, when considered from the standpoint of its height, extends fully from the bottom edge of the assembly to an inner top wall 38 forming the top of the inner liner or casing, said front chamber 35 communicating at the top of the inner liner or casing with a top chamber 37. The chamber 37 is defined between the top wall 38 of the inner liner and the top wall 26 of the outer casing, said top chamber communicating throughout its length with the front chamber 35.

The top wall 38 of the inner liner constitutes a grid, and along its back edge is formed with a downwardly extended flange 40 that can be secured in any suitable manner to the back wall 20 of the outer casing. It will be seen that by reason of this arrangement, the back wall 20 of the outer casing, and the bottom wall 18 thereof, are common to both the outer casing and the inner liner, thus to reduce substantially the cost of materials used in forming the warm air distributor.

In the grid 38 I form a longitudinal series of openings 42, through which air can flow from the interior of the inner liner to the top chamber 37.

A grid slide 44 is embodied in the invention, said grid slide being coextensive in width with the grid 38, and being, additionally, coextensive in length with said grid. The grid slide 44 is formed along its back edge with an upwardly extended flange 46 having slidable contact with the back wall 20 of the outer casing, the front edge of the grid slide 44 being slidably engaged under an angular guide flange 48 secured to the front wall 34 of the inner liner.

In the grid slide 44, I form a longitudinal series of openings 50, and as will be noted from Figure 4, the openings 50 of the grid slide can be brought into or out of register with the grid openings 42, to vary the size of the outlet openings of the inner liner, or close the outlet openings of the inner liner completely. In this way the pressure or flow of air through the duct 18 and inner liner is regulated as desired, the regulated flow being such as to provide for an even distribution of air flow through the length of the assembly.

It is desirable, of course, to provide an operating means whereby the grid slide 44 can be adjusted to selected positions, relative to its associated grid 38. To this end, there is illustrated an upstanding handle 52, secured fixedly at its lower end to the grid slide 44, and projecting upwardly through a longitudinal slot 54 formed in the inclined top wall 26 of the outer casing. The projecting end of the handle 52 can be provided with a knob or button, adapted to be grasped by a user for the purpose of adjusting the grid slide 44 longitudinally of the grid 38, to selected positions.

In the illustrated embodiment of the invention, the warm air distributor is connected in communication with the outlet end of a conventional forced air duct 18, said duct discharging air into the inner liner through opening 21. The air forced into the inner liner will be fed throughout the length of the inner liner, and will pass upwardly through the openings 42, 50, into the top chamber 37.

The air forced into the top chamber 37 will move out of the wall openings 32 in the direction of the arrows shown in Figure 5, passing upwardly along the walls to heat the same.

At the same time, air will be forced into the front chamber 35, passing out of the floor outlet openings 30, and spreading out across the floor 14.

By reason of this arrangement, cold air from the floor will be caused to rise along the walls, as shown by the arrow in Figure 5, said cold air being, at the same time, replaced by warm air discharged through the openings 30.

The construction is such as to permit the flow of air through the openings 32, 30 to be regulated according to the position chosen for the grid slide 44. In certain positions of the grid slide, the proportion of air delivered through the openings will be changed relative to the proportion delivered through the floor outlet openings 30, thus to permit a wide range of adjustment that will be effective to make for even distribution of air flow throughout the length of the assembly.

It is also believed to be of importance to note that in some instances, as for example when the device is being installed in an older home, it may not be practical to

open the wall 12, and in such a case, the opening communicating between the inner liner and the duct 18 would be formed in the bottom wall of the outer casing.

Among other important characteristics of the invention, it is believed that note should be made of the arrangement wherein the entire assembly, comprising both the inner liner and outer casing, can be formed of a minimum amount of material, considering the benefits to be obtained from the use thereof, said material comprising sheet metal readily fabricated to the desired shape.

Additionally, the construction is such as to permit the installation to be varied according to the particular shape or size or room in which the assembly is to be mounted, the warm air distributor being of sectional formation as previously noted herein, with the sections being readily connectible to one another and being assembled to provide for either perimeter heating or spaced, individual heating outlets. When the sections are assembled to provide spaced, individual heating outlets located, for example, under windows, the baseboard can be used as a continuation of a conventional baseboard, and can have any desired outer configuration to harmonize with the conventional baseboard used in the room.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claim.

What is claimed is:

In a baseboard forced warm air distributor, a hollow outer casing including parallel front and rear walls, a bottom wall extending between the front and rear walls, and an inclined top wall extending from the top of said front wall to the top of said rear wall, said front wall having a series of floor air outlet openings therethrough adjacent said bottom wall, said top wall being provided with a series of air outlet openings therethrough; an inner front wall carried by said bottom wall in spaced relation to said front wall to define therebetween a front chamber into which air may be forced, an inner top wall of grid-like formation carried by said inner front wall at the top thereof and extending to said rear wall to define along with said inner top wall, rear wall and bottom wall an inner liner extending longitudinally of said outer casing, said inner top wall being spaced from said outer casing to define in the space therebetween a top chamber in communication with said front chamber throughout the length of the outer casing, means for forcing warm air into said inner liner so that the warm air can pass through said inner top wall into said top and front chambers to be distributed through said outlet openings in the front and top wall and into a room; a grid slidably mounted on the inner top wall, said grid having a longitudinal series of openings for regulating the flow of air from the inner casing to the top chamber, and operating means associated with the grid slide and projecting through the top wall of the outer casing for adjusting the grid slide to selected positions relative to the inner top wall of the inner liner.
